ATTORNEYS

UNITED STATES PATENT OFFICE.

HARRY WEARNE, OF RIXHEIM, GERMANY.

DESIGN FOR WALL-PAPER.

SPECIFICATION forming part of Design No. 33,898, dated January 8, 1901.

Application filed December 18, 1900. Serial No. 40,310. Term of patent 7 years.

To all whom it may concern:

Be it known that I, HARRY WEARNE, a subject of the Queen of Great Britain, and a resident of Rixheim, Alsace, Germany, have invented and produced a new and original Design for Wall-Paper, of which the following is a specification, reference being had to the accompanying drawing, forming a part thereof, in which is represented a section of wall-paper embodying the features of my design, on which strip appear a complete figure and repeats of the same.

The leading feature of my design consists of the representation of an Egyptian water-lily, which appears to rise from the water.

The minor features of the design consist

in the spiral lines at the base of the figure and the general arrangement of the figure, in which three flowering stems apparently arise between opposing leaves.

Having thus described my invention, I claim as new and desire to secure by Letters Patent—

The design for wall-paper as herein shown and described.

In testimony whereof I have signed my name to this specification in the presence of two subscribing witnesses.

HARRY WEARNE.
